UNITED STATES PATENT OFFICE.

IRA A. BURNETT, OF CHICAGO, ILLINOIS.

ADJUSTABLE SANITARY FOUNTAIN-CUP ATTACHMENT FOR DENTAL CUSPIDORS.

Application filed June 6, 1921. Serial No. 475,232.

To all whom it may concern:

Be it known that I, IRA A. BURNETT, a citizen of the United States, and a resident of Chicago, county of Cook, and State of Illinois, have invented certain new and useful Improvements in an Adjustable Sanitary Fountain-Cup Attachment for Dental Cuspidors, of which the following is a specification.

10 This invention relates to improvements in an attachment for dental spittoons or cuspidors of the fountain type, and it consists in certain peculiarities of the construction, novel arrangement and combination of the 15 various parts thereof as will be hereinafter more fully described and specifically claimed.

The main object of the invention is to provide a horizontally adjustable attachment 20 for dental cuspidors of the above named class, whether the same is mounted on a pedestal, or stand, a dental chair, or on the wall of a room, whereby a fountain of water, by preference, in the form of a bubbling or overflowing cup, may be so positioned over the lap by a patient while occupying the dental chair, or by the operating dentist, that the fountain or cup can be readily reached for use in rinsing the mouth 25 or for drinking purposes, without undue distortion of the body of the patient, and can then be manually moved out of the way, or automatically retracted to its normal or initial position.

30 Another object is to so construct and arrange the parts of the attachment, that it can be readily applied to any of the standard makes of dental cuspidors of the fountain type, without material alteration therein, so as to cooperate with the water supply of the 35 cuspidor in furnishing convenient, handy and sanitary means for supplying a fountain of water at a point near the cuspidor or at a reasonable distance therefrom.

40 Still another object is to provide means for automatically turning on the supply of water to the bubbling cup of the attachment in the operation of the extension of the same, and for automatically cutting off such supply when the parts are retracted or returned 45 to their normal positions.

Numerous other advantages and objects of the invention will become obvious from the following description and explanation.

50 In the accompanying drawings, which

serve to illustrate an embodiment of the invention—

Fig. 1 is a view in elevation of a dental cuspidor of the fountain type showing my attachment mounted thereon.

Fig. 2 is a greatly enlarged vertical sectional view taken on line 2—2 of Fig. 1 looking in the direction indicated by the arrows and showing the faucet or outlet pipe for drinking water broken for the convenience of illustration.

Fig. 3 is a plan sectional view taken on line 3—3 of Fig. 2.

Fig. 4 is a cross-sectional view taken on line 4—4 of Fig. 2.

Fig. 5 is a fragmental plan view taken on line 5—5 of Fig. 2.

Fig. 6 is a vertical sectional view taken on line 2—2 of Fig. 1 but illustrating a modification in the construction of the attachment.

Fig. 7 is a similar view illustrating still another modification in the construction of the attachment.

Corresponding numerals of reference refer to like parts throughout the different views of the drawings.

In the present instance, I have shown my attachment in connection with a pedestal supported fountain cuspidor, and in the following description and explanation will so describe and explain it, yet it will be readily understood by those skilled in the art to which the invention pertains, that the cuspidor may be supported by a stand, a wall support, or by a suitable support attached to the dental chair, and for this reason, I desire to be understood as not limiting myself in any manner as to the construction of the support for the cuspidor bowl.

Referring now to Fig. 1 of the drawing, the reference number 10 designates a pedestal on the upper end of which is mounted an arm 11 of the ordinary or any preferred design, which carries on one of its ends a cuspidor bowl 12 and on its other end a finger bowl 13. The arm 11, as well as the pedestal 10, is hollow and has extended therethrough, as is well known, outlet pipes or conduits which communicate at their upper ends with said bowls, and lead at their other ends, to any suitable point for discharge.

The pedestal 10 and arm 11 also has extended therethrough in a well-known way, a water supply pipe which is connected to a fixture 14 of any well known construction,

which fixture is vertically mounted on the arm 11 and extends upwardly between the bowls 12 and 13, and is provided near its upper end with one or more faucets 15 which are located so as to discharge water in the cuspidor bowl. The fixture 14 is provided with a shut-off or controlling valve 16 near its juncture with the arm 11 and on its upper portion with a valve casing 17, from which the faucet or faucets 15 for the bowl 12 are extended. This valve casing is also provided with a valve 18 for controlling the flow of water through the faucet or faucets 15, and has extended through its upper end 15 a nozzle or pipe 19 to which the ordinary goose-neck shaped faucet or outlet pipe for drinking water is fitted at its lower end. So far as described, the construction of the parts named is of the ordinary or well-known kind.

In mounting my attachment on the fixture 14, the faucet or outlet pipe for drinking water is removed from the pipe 19 at the upper end of the valve casing 17, and in lieu thereof the lower end of the upright supply tube 20 of my attachment is screwed onto the pipe 19 as shown in Fig. 2, or the same may be otherwise suitably mounted on the upper portion of the valve casing 17 and in communication therewith.

As is clearly shown in Fig. 2 of the drawings, the attachment consists of the upright supply tube 20 having a number of transverse openings extended diametrically 35 and horizontally therethrough one above the other. The lowermost pair of these openings has fitted therein a tube 21, the uppermost one, a tube 22, and the intermediate pair of said openings, the tube 23, each 40 of which is closed at one of its ends by a screw cap 24, each of which caps is by preference ornamented with a globular projection 25 located on its outer surface. Near each of their ends the tubes 21 to 23 inclusive 45 are connected together and braced by means of vertically disposed bars 26, which bars are provided at suitable distances apart with openings of the proper size to fit snugly around their respective tubes. The bar 26 50 at the outer ends of the horizontal tubes is provided in its upper portion with a transverse opening 27 through which is extended a short tube 28 which communicates at one of its ends with the upper portion of the 55 supply tube 20 and at its other end with the uppermost tube 22 near the outer end of the latter. This last mentioned tube, as well as the tube 21, has its cavity adjacent its screw cap 24 enlarged as at 29 for the purpose to 60 be presently explained.

Fitted in or secured to the upper end of the supply tube 20 of the attachment, is the lower end of a faucet or outlet pipe 30 for drinking water, which is provided just 65 above its juncture with the tube 20

with a valve 31 to control the flow of water through said pipe. Telescopically fitted in the inner end of each of the tubes 21, 22 and 23, are the inner ends of tubes 32, 33, and 34 respectively, which are connected 70 at their opposite ends to an upright tube 35 which is closed at its lower end preferably by means of a screw cap 36 of an ornamental design.

By reference to Fig. 2, it will be seen that 75 the tubes 32 and 33 communicate with the cavity of the tube 35, while the tube 34 does not have communication with said tube, but is fixed to the wall thereof in any suitable manner.

The tube 35 is provided on its wall opposite the adjacent ends of the tubes 32 and 33, with a handle bracket 36 to be used for moving the tubes 32 to 34 inclusive back and forth with respect to the fixed tubes 21 to 85 23 inclusive. Mounted on the upper portion of the upright tube 35 is an overflow bowl 37 of glass or any other suitable material. Within this bowl and mounted on top of the tube 35 is a cup 38 of any suitable 90 material which has extended centrally through its lower portion a tube 39 which extends into the tube 35 and from thence into the uppermost tube 33 of the slidable tubes. It will be understood that the parts 95 of the attachment which are exposed to water are fitted in any well-known way so as to prevent leakage. In its periphery between the bowl 37 and cup 38, the tube 35 is provided with a number of openings 40 100 to permit the passage of water from the bowl 37 into the tube 35 from whence it will escape through the tubes 32, 21, and an outlet tube 41, which may lead to any suitable point for discharge.

Each of the tubes 21, and 22, has threaded on its inner end a ring nut or packing gland 42 which nuts surround the tubes 32 and 33, yet in such a manner as to permit of sliding movement of the latter. Between the glands 42 and the tubes on which they are mounted is located packing 43 of a suitable kind. The inner end of the tube 23 is provided with an inturned projection 44 which is adapted to operate in a slot 45 in the lower portion of the tube 34 and to engage a portion 46 of the tube 34 at its inner end to restrict the outward movement of the slidable tubes with respect to the fixed tubes of the attachment.

Secured at one of its ends to a projection 47 on the cap 24 which closes the outer end of the tube 23, is a spiral spring 48 which has its other end secured to a suitable projection 49 within the end of the tube 34 adjacent the cup bearing tube.

Pivoted near one of its ends on a suitable bracket 50 with which the wall of the waste water tube 35 or cup bearing tube is provided near the end of the tube 34 adj-

cent thereto, is a locking bar 51 which is adapted to engage the inner end of the tube 23 as is clearly shown in Fig. 3 of the drawings, and thus prevent the tubes 32 to 34 inclusive being retracted within the tubes 21 to 23 inclusive in connection with which they are mounted for telescopic engagement, by the action or tension of the spring 48, or accidentally when said spring is not employed. The screw cap 24 which closes the outer end of the tube 22 is provided on its inner surface with a cone-shaped plug 52 which is employed to close the inner end of the tube 33 when the cup bearing or waste water tube 35 is retracted to the normal position of the parts of the attachment. In order that water may enter the tube 33 through the pipe section 28 which leads from the supply tube 20 on a slight movement outwardly of the tube 33 the outer end of the cavity in the tube 22 is enlarged as at 29, see Fig. 2 of the drawing.

For the purpose of permitting the exhaust or waste water to be discharged from the outer end of the tube 21 and from thence through the outlet tube 41, the outer end of the cavity in the tube 21 is also enlarged as at 29, see Fig. 2 of the drawings.

From the foregoing, and by reference to Fig. 2, it will be understood that the pipe section 28, and the tubes 22, 33 and 39, constitute the conduit for supplying water to the cup 38 from which it will overflow into the bowl 37 and pass therefrom through the openings 40 into the cup bearing or waste water tube 35 from whence it will pass through the tubes 32, 21 and 41 which constitute the outlet conduit of the attachment of the above described construction.

In Fig. 6 I have shown a modification in the construction of the attachment which consists in the employment of an upright water supply tube 53 which is adapted for engagement and communication with the upper end of the nozzle or pipe 19 of the valve casing 17 of the water fixture 14 in very much the same manner as the tube 20 of the first above described construction and above set forth.

The supply tube 53 of the modification now under consideration, may have mounted on its upper end the lower end of the faucet or outlet pipe 30 for drinking water, which is, as in the other construction, provided just above its juncture with the tube 53 with a valve to control the flow of water through the said pipe. The tube 53 is provided in its wall about midway between its ends with an opening 54 in which is fitted against leakage a short pipe section 55 which has therein a centrally disposed cone-shaped plug 56 which is spaced from the inner surface of the wall of the member 55 and has openings 57 in its support between said plug and the member 55 for the passage

of water. Fitted in the outer end of the member 55 or secured thereto against leakage is a horizontally disposed tube 58 which forms a part of the water supply conduit from the tube 53 to the cup 38 of the modified form of the attachment now being described.

Fitted around a portion of the tube 53 and the upper part of the nozzle or pipe 19 is a sleeve 59 which has communicating with its lower portion an outlet pipe 60 which may lead to any suitable point for discharge. Surrounding the pipe section 55 and tube 58 is another tube 61 of larger diameter than the tube 58, which has one of its ends fitted in an opening 62 in the wall of the sleeve 59 and extends in parallelism with the tube 58 to about the outer end of the latter. Located in the tube 61 for telescopic movement therewith is a tube 62 which communicates at its outer end with a cup bearing or waste water tube 63 which is vertically mounted on the tube 62 and may be equipped with a handled bracket 36 as in the other construction.

Slidably located in the outer end of the tube 58 is a tube 64 which is extended into the tube 62 and has communication with the cup 38 through an elbow pipe 39 which is vertically supported in the tube 63 by a horizontally disposed perforated frame 65 secured to the inner surface of the cup bearing tube. This last named tube has mounted on its upper portion the bowl or basin 37 and is provided between said basin and the cup 38 with perforations 49 for the passage of the overflow water from said cup. The outer end of the tube 61 has mounted thereon a ring nut or packing gland 66 which surrounds the tube 62 in such a way as to permit slidable movement of the tube 62 through said ring and with respect to the tube 61.

Located between the gland or ring 66 and the adjacent end of the tube 61 is a gasket or packing ring 67 of any suitable kind used to prevent leakage. That end of the tube 58 adjacent the supply tube 53 has its cavity enlarged as at 29 for the same purpose as the enlargement 29 in the tube 22 of the first above described construction. By the above described construction of the modified form of the attachment it is evident that the pipe section 55, tubes 58, 64, and 39, constitute the water supply conduit from the supply tube 53 to the cup 38 and that the cup bearing or waste water tube 63 and the tubes 60, 61 and 62 constitute the conduit for the outlet of water from the cup 38 and overflow basin 37.

On its lower portion near its outer end, the tube 61 has a depending and laterally apertured bracket 68 through which is slidably extended a horizontally disposed stop rod 69 which has on its inner end a knob 70

- to contact with the bracket 68 when the cup bearing tube 63 is adjusted to its outermost position, so as to prevent disconnection of the tubes 62 and 64 from the tubes 61 and 58 respectively. The outer end of the rod 69 is suitably connected to the lower portion of the cup bearing tube 63 on its surface opposite its handle bracket. The sleeve 59 which surrounds the supply tube 53 and a portion of the pipe 19 is held in spaced relation around said parts by means of suitable collars 71 and 72 each of which may be equipped with a packing 73 and a suitable gland 74 therefor.
- 15 In the constructions above described, the attachment is constructed for adjustment in a horizontal plane only, but in the modified construction shown in Fig. 7 and which will now be described, I have shown means not 20 only for the adjustment of the cup 38 and its bowl in a horizontal plane, but also for pivotal adjustment therefor.

The present modification consists of an upright water supply tube 75 which is adapted for connection at its lower end with the nozzle 19 or outlet pipe from the upper end of the valve casing 17 of the water fixture 14 and may be equipped at its upper end with an outlet pipe or faucet 30 for drinking water, which faucet or pipe may have a controlling valve 31 as in the other described constructions.

Surrounding the upper portion of the supply tube 75 is a sleeve 76 which has on its wall a pair of spaced apertured lugs 77 and below the lowermost of said lugs a tubular member 78 secured at one of its ends in any suitable manner to the tube 75 and provided at its other end with a ball or knob 79 for ornament. This tubular member 78 has extended from its lower portion a tubular section 80 which is located near the outer end thereof and between said tubular section 80 and the wall of the tube 75, the member 78 has connected thereto one end of an outlet pipe 81 which may lead to any suitable point for discharge. Extended at its upper end through suitable registering openings in the sleeve 76 and supply tube 75 is an elbow pipe 82 which extends through a suitable opening in the upper surface of the extension 78 and thence through the tubular section 80 a slight distance below the lower end of said section.

Vertically located in the apertures of the lugs 77 is a pintle 83 on which is loosely mounted between the lugs 77 a pair of collars 84 each of which has pivotally connected thereto one end of an arm or lever 85 of a bracket, which is designated as a whole by the numeral 86 and is in the form or well known construction of a lazy-tongs. This bracket or lazy-tongs is pivotally connected at its end opposite the pintle 83 to a collar 87 which surrounds and supports

the upright cup bearing or waste water tube 88 of the modified form now under consideration. This cup bearing tube may be provided as in the other constructions, with a handle bracket 36 for the manipulation of the device, and has mounted on its upper portion a bowl 37, and within said bowl and on its top a cup 38 as in the other constructions.

Between the lower end of the cup 38 and the bowl 37 the tube 88 is provided with perforations 40 for the overflow water from the cup 38 and from said bowl. Extended downwardly through the cup 38 and into the tube 88 to near its lower end is a tube 89 which has communicating with its lower portion an elbow pipe 90 which is extended laterally through an opening in the wall of the tube 88 and thence downwardly and transversely through a tubular member 91 secured at one of its ends to the wall of the tube 88 near its lower end and having at its other end a knob 92 or other suitable ornament. The member 91 is provided on its lower portion with a downwardly extended pipe section 93, and it will be observed by reference to Fig. 7 that the elbow pipe 90 is extended at its lower end beyond the lower end of said pipe section. Connecting the lower end of the elbow pipe section 82, which leads from the supply tube 75, to the lower end of the elbow pipe section 90 is a flexible tube 94 which may be of any suitable length. This flexible connection 94 is surrounded by a flexible tubular connection 95 which is of larger diameter than the connection 94 and has one of its ends secured to the tubular extension or member 80 and its other end to the tubular member 93 of the part 91 on the movable or cup bearing tube.

By the foregoing arrangement and construction of the parts of the modified form of the attachment now under consideration, it is manifest that the elbow pipe section 82 leading from the supply tube 75, the flexible connection 94, the elbow pipe section 90 leading into the movable tube 88, and the pipe 89 communicating at its upper end with the cup 38 form the conduit for the supply of water from the tube 75 to said cup.

It is further apparent that the cup carrying tube 88, the extension 91 thereon, the flexible connection 95, the tubular extension 78, and the pipe 81 leading from the latter member, form or constitute the outlet conduit from said cup and the overflow basin 37 mounted below and around the same. By means of the last described extensible connection between the supply tube and the movable tube of the attachment, it is evident that the movable tube carrying the cup on its upper end can not only be adjusted horizontally with respect to the supply tube, but can also be turned sidewise with respect thereto.

To more securely support the arms or levers 85 of the lazy-tongs 86, I may secure on each side or face of the tongs 86 a pair of parallel guide rails 96 having one of their ends fastened to the collar 87 and their other ends extended horizontally a suitable distance towards the pintle 83 when it is apparent that the pivots 97 of the arms 85 of the lazy-tongs will ride on and between the said rails.

Having thus fully described my invention, what I claim as new and desire to secure by Letters Patent is—

1. In an attachment of the class described, the combination with a water-supply-tube adapted for communication with a supply of water, of another tube mounted thereon for horizontal adjustment with respect thereto, a cup mounted on said adjustable tube, horizontally extensible means for the passage of water connecting the supply tube to said cup, and means for automatically closing said water passage on the retraction of the movable tube.

2. In an attachment of the class described, the combination with a water-supply-tube adapted for communication with a supply of water, of another tube mounted thereon for horizontal adjustment with respect thereto, a cup mounted on said adjustable tube, extensible means for the passage of water connecting the supply tube to said cup, and means for automatically opening said water passage on the initial horizontal movement of the movable tube from the supply tube.

3. In an attachment of the class described, the combination with an upright water-supply-tube adapted for communication at its lower portion with a supply of water, of a waste-water-tube mounted in parallelism with the supply-tube, a bowl mounted on said waste-water-tube in communication therewith, a cup on said tube within said bowl, an extensible water-supply conduit communicatingly connecting the supply-tube and said cup, means at one end of said

conduit for automatically closing the same on the retraction of the waste-water-tube to its normal position, and an extensible water-outlet conduit supported by the supply tube and communicating at one of its ends with the waste-water-tube.

4. In an attachment of the class described, the combination with an upright water-supply-tube adapted for communication at one of its ends with a supply of water, of a waste-water-tube mounted in parallelism with the supply-tube, a bowl mounted on said waste-water-tube in communication therewith, a cup on said tube within said bowl, an extensible water-supply-conduit communicatingly connecting the supply-tube and said cup, means at one end of said conduit for automatically closing the same on the retraction of the waste-water-tube to its normal position and for automatically opening said conduit when said waste-water-tube is moved from the supply-tube, and an extensible water outlet conduit supported by the supply-tube and communicating at one of its ends with the waste-water-tube.

5. In an attachment of the class described, the combination with an upright water-supply-tube adapted to be mounted at its lower end on a water-supply nozzle of a fountain cuspidor, of a plurality of tubes extended transversely through the said water-supply-tube, a plurality of tubes located in said transversely disposed tubes for telescopic movement therein, a waste-water-tube vertically mounted on the outer ends of the movable tubes, a bowl mounted on the waste-water-tube in communication therewith, a cup mounted on said tube within said bowl and having communication with one of said movable tubes, means communicatingly connecting the upper portion of the water-supply-tube with the uppermost transverse tube thereon, and means communicating with the lowermost transverse tube on the supply-tube for the discharge of water.

IRÀ A. BURNETT.
